CLAIM

The ornamental design for a case for mobile telephone, as shown and described.

DESCRIPTION

FIG. 1 is a top, front and right side perspective view of a case for mobile telephone showing my new design;

FIG. 2 is a bottom, rear and left side perspective view thereof, showing the rear support stand in a stowed position;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, rear and right side perspective view thereof, showing the rear support stand in an extended position; and, FIG. 10 is an enlarged view of portion 10 in FIG. 1.

The dot-dash broken lines in FIGS. 1 and 10 form no part of the claimed design and delineate a portion of the claimed design that is shown on an enlarged scale in FIG. 10. The dash-dot broken lines throughout the drawing figures form no part of the claimed design and illustrate portions of the case for mobile telephone that form no part of the claimed design.
